CLAIM

The ornamental design for a bell ornament, as shown and described.

DESCRIPTION

The patent or application file contains at least one drawing executed in color. Copies of this patent or patent application publication with color drawings(s) will be provided by the Office upon request and payment of the necessary fee.

FIG. 1 is a perspective view of a bell ornament showing my new design;

FIG. 2 is a front elevation view thereof, the rear elevation view being a mirror image;

FIG. 3 is a left side elevation thereof, the right side elevation view being a mirror image;

FIG. 4 is a top plan view thereof; and,

FIG. 5 is a bottom plan view thereof.
